7898 X Dedidah Bookwith.

Letters Patent.

The Schedule referred to in these Letters Patent, and making part of the same, containing a description in the words of the said Dedidah Bookwith himself of his Improvement in the metallic pump.

To all to whom these presents shall come,

Be it known that I, Dedidah Bookwith, of the Town & County of Oneonta, State of New York, have invented a new & useful metallic pump & that the following is a full & exact description of the construction & operation of the said machine as invented by me.

A as exhibited on the accompanying draft represents the tubes thru' which the water passes. .... B represents stationary poppet valves. .... C moving valves. .... D piston rods attached to moving valves & passing thro' cap G. .... E pendulum rod connected with pinion wheel. .... F pinion wheel attached to pendulum rod by a pin passing thro' cap G. .... G cap or valve attached to the tubes. .... H block attached to piston rods.

I coupling blocks, to secure bottom & discharge pipes. ....

At A, the water is received at B, & discharged at C. ....

The machine is moved, by application of power to the pendulum rods, & at each sweep of which the water is drawn in & discharged alternately thro' the tubes.
